UNITED STATES PATENT OFFICE

162,796

CHILD'S TOY

Walter Dorn, Seattle, Wash.

Application August 2, 1948, Serial No. 147,879

Term of patent 3½ years

(Cl. D34—15)

To all whom it may concern:

Be it known that I, Walter Dorn, a citizen of the United States, residing at Seattle, in the county of King and State of Washington, have invented a new, original, and ornamental Design for Child's Toy, of which the following is a specification, reference being had to the accompanying drawing, forming part thereof:

Fig. 1 is a perspective view of a child's toy embodying the present design.

Fig. 2 is a top or plan view of the same.

The rear or back portion of the skirt portion of the doll element is substantially identical to the front and the rear or back of the body portion is substantially plain.

I claim:

The ornamental design for a child's toy, as shown and described.

WALTER DORN.
